UNITED STATES PATENT OFFICE.

WILLIAM J. MCKEE, OF PITTSBURG, PENNSYLVANIA.

DESIGN FOR A SOUVENIR MEDAL.

SPECIFICATION forming part of Design No. 21,425, dated March 22, 1892.

Application filed June 6, 1891. Serial No. 395,388. Term of patent 3½ years.

To all whom it may concern:

Be it known that I, WILLIAM J. MCKEE, a citizen of the United States, residing at Pittsburg, in the county of Allegheny and State of Pennsylvania, have invented and produced a new and original Design for a Columbus Souvenir Medal, of which the following is a specification, reference being had to the accompanying drawings, forming part thereof.

10 Figure 1 is the obverse side of the medal, and Fig. 2 is the reverse side of the same.

The outline of the medal is circular in form, and upon each side of the same there is described a square touching at its four corners the outer circle, and within this square are described three concentric circles, the outer circle being tangent to the square.

15 On the obverse face the innermost circle is divided into four quarters by crossed bands of stars and letters, and in the four quarters of this circle are placed four small circles. In the horizontal angles of the square are two other circles, and outside of the square and also in the vertical corners of the square and 20 between the three concentric circles are spaces for any suitable matter.

On the reverse side of the medal there are in the segments of the outer circle four small circles, and within the horizontal angles of the outer square there are two other small circles, 30 each bearing spaces for any desired matter. In the upper angle of the outer square is a head of Columbus. Inside the smaller of the concentric circles is described a square with sides parallel to those of the outer square. In 35 this square from the upper angle is suspended an American flag with thirteen stars thereon, surmounted by a circle bearing a seven-pointed star.

40 What I claim is—

1. The design for a medal, herein shown and described.

2. The design for the obverse side of the Columbus souvenir medal, as shown and described.

3. The design for the reverse side of the Columbus souvenir medal, as shown and described.

45 WILLIAM J. MCKEE.
